UNITED STATES PATENT OFFICE.

JAMES B. MORTON, OF CHICAGO, ILLINOIS.

COMPOSITION SHINGLE-TILE.

1,188,472.

Specification of Letters Patent. Patented June 27, 1916.

Application filed February 18, 1915. Serial No. 9,003.

To all whom it may concern:

Be it known that I, JAMES B. MORTON, a citizen of the United States, residing at Chicago, in the county of Cook and State of Illinois, have invented a certain new and useful Improvement in Composition Shingle-Tile, of which the following is a specification.

My invention relates to that class of roof-coverings, which are designed to take the place of the wooden shingles, tile or slate, the slate being objectionable due to its cracking, and falling from the roof; the tile because of its great weight, and consequently the increased cost of building construction to support it, while the wooden shingles have to be frequently replaced from time to time, besides being subject to the deleterious action of the weather.

My invention has for its object to produce a composition tile comprising gypsum and asphalt which will not be appreciably heavier than the wooden shingle, which will not crack, and which will not be affected by the action of the weather, and has for its further object to provide a construction which when utilized can be followed by any workman, and which will not require skilled labor for covering the roof.

My means of accomplishing the foregoing objects may be more readily understood by having reference to the accompanying drawings which are hereunto annexed and are a part of this specification, in which:

Figure 1, is a side elevation of a portion of a roof provided with my improved composition shingle. Fig. 2, is a cross section of the same. Fig. 3, is a top or plan view of one of the shingles. Fig. 4, is an end elevation. Fig. 5, is an end elevation of the other end of the shingle. Fig. 6, is a bottom view. Fig. 7, is a cross-section taken on the line $x-x$ in Fig. 3.

Similar reference numerals refer to similar parts throughout the entire description.

As shown in the drawings, the shingle 8, tapers from its lower edge 9, to its upper edge 10. On the bottom side of the shingle is formed a shoulder 11, the edge 12 of which tapers inwardly and is adapted to engage the upper edge 10, of the shingles of the row upon which it is superimposed. The edge 10, is beveled on the bottom side of the shingle as at 13, this beveling being to conform to the tapered face 12, of the shoulder or rib 11. There is a laterally ex-

tended portion 14 at one side of the shingle 8, which is adapted to be overlapped by the next adjacent shingle, a shoulder 15, being formed adjacent the upper edge 10 of the shingle. This shoulder serves the double purpose of holding the shingles the required distance apart to reproduce the appearance of a wooden shingled roof, and has the further purpose of preventing the water from beating up underneath the superimposed course of shingles. It will be noted that it substantially coincides with the lower edge of the superimposed course of shingles. A similar portion 24 is formed at the other end which is adapted to overlie the portion 14 on the adjacent shingle, these laterally extended portions being only one-half as thick as the remaining part of the shingle which results in producing a uniform thickness of the shingles when they are laid. A groove 16, is formed in the top of the laterally extended portion 14, and tapers upwardly, the purpose of which will be hereinafter explained.

Where it is found desirable to carry out the appearance of a shingled roof to the fullest extent, a shoulder 20 is formed on that portion of the shingle which overlaps the groove. The inner edge of this shoulder is tapered as clearly shown in Fig. 6. This covers up the lower end of the groove 16, so that it is not visible, and yet provides for draining water therefrom by means of the tapered wall 21.

The roof is laid with my improved shingles in the following manner: A starting strip 17, is fastened to the lower edge of the roof and this is the only part of the work which requires the service of an expert. This starting strip is provided with a beveled edge, which engages the tapered face 12 of the shoulder or rib 11 on the bottom of the shingle, as is clearly seen in Fig. 2. If this strip is laid accurately the rest of the work is merely fitting the shingles into place. While the tapered face 12 on the shoulder 11 serves to hold the shingles securely in place, it may be found desirable in practice to nail them in addition to fastening them in this manner, and for this purpose holes 18, may be provided at or near the upper corners of the shingles.

It will be obvious from an inspection of the drawings, that the portion 24 of the adjacent shingle overlaps the laterally extended portion 14, and in the event of any water

beating in under this shingle, the groove 16, will catch and drain it downwardly and prevent its reaching the edge of the shingle and consequently the interior of the roof.

5 It will be apparent from the foregoing description that skilled labor is not required to lay the tiles or shingles, for if the starting strip has been put in place correctly, the rib 11 will serve by its engagement of the upper 10 edge of each course of shingles, to hold them firmly in position, while the shoulder 15 will hold them true. It is of course obvious that right and left half shingles will have to be made for each alternate course at the ends 15 of the roof.

Having described my invention what I regard as new and desire to secure by Letters Patent is:

1. A roofing comprising composition shingles, each of the shingles having a reduced laterally extending portion, a shoulder adjacent the upper edge of the shingle and formed by an unreduced portion of the

laterally extending portion, the opposite edge of the shingle being cut away beneath 25 to receive the laterally extending portion of the adjacent shingle, whereby one edge thereof engages the shoulder to form a roof simulating a shingle roof.

2. A roofing comprising composition shingles, each of the shingles having a lateral extension of substantially half the thickness of the shingle, a shoulder formed adjacent the upper edge of the shingle and forming a part of the extension, said shoulder adapted 35 to engage one edge of the adjacent shingle for providing a clearance between the shingles, said lateral extension having a longitudinal groove for directing water from the joint between adjacent shingles.

In testimony whereof I have signed the foregoing specification.

JAMES B. MORTON.
